UNITED STATES PATENT OFFICE.

CLAI'RE T. KEIGLEY, OF WOODWARD, ALABAMA, AND GEORGE LAMBERTON, OF LORAIN, OHIO.

GAS CONTROL FOR COKE OVENS.

Application filed July 7, 1921. Serial No. 482,953.

- This invention relates to gas controls for regenerative coke ovens, and more particularly to means for shutting off the gas to the oven when the supply fails.
- 5 The principal object of the invention is to provide control mechanism that will automatically shut off the gas to a coke oven when the pressure in the gas holder falls below a predetermined pressure.
- 10 Another object is to provide control mechanism that is readily adaptable to the ordinary form of coke ovens without material change.

In the drawings, Figure 1 is a diagrammatic elevation of the pusher and coke sides of a battery of coke ovens, and a gas holder having our invention applied thereto.

Figure 2 is a diagram of the control circuits used to operate the motor for the gas valves of one side of the furnace.

Referring particularly to the drawings, A and B designate the pusher and coke sides, respectively, of a battery of coke ovens of the Kopper's type having the usual gas mains 2 for supplying gas to the ovens. The mains 2 have a plurality of branch pipes 3 leading to burners 4, which enter the vertical flues of the ovens, and each pipe 2 is provided with a control valve 5. The several control valves 5 on the pusher side of the ovens are connected to a flexible operating member such as a cable 6, which is trained over suitable sheave wheels 7 and carries a counterweight 8 on its one end and has its other end connected to a reversing machine 9, operated by a motor 10.

The several control valves 5 on the coke side of the ovens are connected to a flexible operating member or cable 11 which is trained over suitable sheave wheels 12 and carries a counterweight 13 on its one end and has its other end connected to a reversing machine 14, operated by a motor 15.

Each of the burners 5 have a decarbonizing valve 16 connected therewith. The decarbonizing valves 16 on the pusher side of the oven are connected to a counterweighted flexible member or cable 17 which is adapted to be operated by a decarbonizing valve operating machine 18, having a motor 18', and the decarbonizing valves 16 on the coke side are connected to a similar counterweighted flexible member or cable 19 which

is operated by a decarbonizing valve operating machine 20 having a motor 20'.

55 A stack or conduit 21 is provided for the products of combustion and has reversing dampers 22 and 23 connected, respectively, by flexible members 24 and 25 secured to sheave wheels 9^a and 14^a, which in turn are 60 driven by reversing machine 65 so that the draft from one side of the oven to the other may be reversed when the firing is reversed from one side to the other.

Air valves 75 are mounted on the pusher 65 side of the stack 21 and other air valves 76 are mounted on the coke side of the stack, and are adapted to be opened or closed by cables 77 and 78, respectively, which are secured to sheave wheels 9^a and 14^a, respectively, in such a manner that when the dampers 22 and 23 are lowered, the respective air valves 75 and 76 will be opened and vice versa.

70 A gas holder 27 is adapted to receive and 75 store gas after the by-products have been removed therefrom, and is provided with a vertically movable bell 28, a supply main 29 enters the gas holder 27 at the bottom, and outlet mains 30 and 31 lead therefrom. 80 The outlet main 30 is provided with branches 32 and 33 leading to the burner supply mains 2, and the outlet main 31 leads to distributing branches (not shown) and is provided with an automatic shut-off valve 85 34, adapted to shut off the flow of gas therethrough when the supply of gas in the gas holder fails.

The valve 34 is operated by means of a 90 flexible cable mechanism 35 connected with the bell 28 of the gas holder 27.

A contactor 36^a which is mounted on the bell 28 of the gas holder, is adapted to engage with and complete a circuit through the contacts 36 and 37, which are mounted 95 on the base or body portion of the holder, when the volume or pressure of gas in the holder 27 is lessened to the predetermined point at which the bell 28 is lowered enough to cause the contactor 36^a to bridge across the contacts 36, 37.

100 Bridging of the contacts 36 and 37 by the contactor 36^a will complete a control circuit to operate the mechanism for controlling the circuits to the motors 10 or 15, according 105 to which side of the oven is being fired.

since the circuit is through switches 39 and 40 for the motors 10 and 15, respectively, and these switches are closed when their respective sides of the ovens are firing.

5 The control circuits necessary in carrying out this invention are shown in the diagram of Figure 2 as combined with the ordinary automatic control circuits for the motors of the gas valves and decarbonizing 10 valves. The heavy lines denote the new circuits, necessary to carry out the invention.

Assuming that the ovens are being fired on the pusher side of the battery of ovens, and that the gas supply in the holder 27 15 has decreased sufficiently to allow the bell 28 to drop, closing contactors 36 and 37, a control circuit will thus be established through contactor E, as follows:—plus line through the contactor 36^a and contacts 36—37 20 through wire 42 to switch 39. Since, as shown in the drawings, the pusher side of the oven is being fired, the switch 39 will be closed. The circuit is therefore through switch 39 to a wire 43, through a coil of 25 contactor E to wire 44 and to minus line, thus closing contactor E. Contactor E is adapted to be normally energized by an electric circuit controlled by a standard clock control (not shown), so as to close the 30 circuit to the timing motor F at predetermined intervals, which timing motor will operate the switches controlling the electric circuits to the valve operating motors 10 and 15 to cause a reversal of the valves at 35 predetermined intervals. The closing of contactor E closes the armature circuit to a timing motor F, setting it in motion to operate the timing mechanism Y, which in turn actuates the switch a or d according 40 to whether the gas is burning on the pusher or coke side.

With the gas burning on the pusher side of the ovens as here shown, switch a would be closed first, thus closing a circuit from 45 plus line, to wire 46, to limit switch 47, for decarbonizing valve motor 20', through the two top contacts 47^a, 47^b of this switch to magnet coil of magnetic switch X on the controller for decarbonizing valve motor 50 20' to minus side of line as shown. The closing of switch X on the controller completes the armature circuit of decarbonizing valve motor 20', which motor will run until limit switch 47 has moved from position 55 m—m to position n—n. In other words, contacts n—n will be under the fingers of the limit switch in place of the contacts m—m. When this takes place, a control circuit through the magnet coil of switch 60 X of the controller for the motor will be opened, thus opening switch X and stopping decarbonizing valve motor 20'.

As soon as the limit switch 47 has moved from position m—m to position n—n a circuit will be established from wire 46 through

contacts o—o of limit switch 47 to contacts p—p on gas valve limit switch 49 to wire 50, to magnetic coil of contactor 51 of the controller for the gas valve motor 10 to the minus line. Closing of the contactor 51 completes armature circuit of gas valve motor 10 as follows:—from plus line through wire 52 to wire 53, contactor 51 and wire 54, to armature of gas valve motor 10, then through wire 55 to minus line. The gas 75 valve motor 10 will run until limit switch 49 is moved from position r—r to position s—s when the circuit will be broken to motor 10 and the motor stopped. The limit switch 49 is so adjusted that the gas valves 80 operated by the motor 10 will be in closed position when the motor 10 is stopped. At the same time switch 39 will open, thus opening central circuit through one-half of magnet coil of the double coil contactor E, 85 stopping timing motor F, thus preventing any further operation of the gas reversing machinery.

When the contacts 36 and 37 are connected 90 by the bridge contactor 36^a so as to thereby close the control circuit to the contactor E, a circuit is also closed to an audible signal such as a Klaxon horn 60, as follows:—from wire 42 through wire 61, thence through the windings of the horn 60, to wire 62, push-button 63, and wire 64 to minus line as shown, the purpose of this audible 95 signal is to call the attention of the operator to the fact that the gas is being shut off from the ovens. 100

While we have described and illustrated only one form of our invention it will be understood that we do not wish to be limited thereto, since various modifications may be made within the scope of the appended 105 claims.

We claim:

1. In a gas control system for by-product coke ovens, the combination with a series of 110 gas burners on each side of said ovens for heating said ovens, a gas holder, mains leading from said gas holder to said burners, and controlling and reversing valves for controlling the flow of gas from said mains to said burners, of electric motors for operating said valves, electric circuits for said 115 motors, and means operable by said gas holder for completing the electric circuits to said motors to cause said motors to close said valves when the gas in said gas holder falls below a predetermined pressure. 120

2. In a gas control system for by-product coke ovens, the combination with a series of 125 gas burners on each side of said ovens for heating said ovens, a gas holder, conduits leading from said gas holder to said burners, controlling and reversing valves for controlling the flow of gas from said conduits to said burners, electric motors for operating said valves, and electric circuits for said 130

- motors, and electrically operated means for normally closing said electric circuits to said motors at predetermined intervals to cause the operation of said valves, of means operable by said gas holder when the gas in said gas holder falls below a predetermined pressure for energizing said electrically operated means to thereby cause said means to close the circuits to said motors whereby said 10 motors will operate to close said valves.
3. In a gas control system for by-product coke ovens, the combination with a series of gas burners on each side of said ovens for heating said ovens, a gas holder, conduits 15 leading from said gas holder to said burners, controlling and reversing valves for controlling the flow of gas from said conduits to said burners, electric motors for operating said valves, and electric circuits for said 20 motors, and electrically operated means for normally closing said electric circuits to said motors at predetermined intervals to cause the operation of said valves, of an electrical circuit for energizing said electrically operated means for closing the circuits to said 25 motors, and electrical contacts carried by said gas holder and adapted to close said
- electrical circuit for energizing said electrically operated means for closing the electric circuits to said motors when the gas in said 30 holder falls below a predetermined pressure.
4. The combination with a coke oven having gas burners for heating the same, valves for controlling the flow of gas to said burners, an electric control means for alternately opening and closing said valves, and an electrically actuated contact element for said control means, of a gas supply for said burners, a pressure responsive contact element associated with the gas supply, said pressure responsive contact being operatively connected through a circuit with said electrically operated contact to effect the operation of said control means to close said 40 valves when the gas supply pressure falls below a predetermined minimum.

In testimony whereof I have hereunto signed my name.

CLAI'RE T. KEIGLEY.

In testimony whereof, I have hereunto signed my name.

GEORGE LAMBERTON.
